UNITED STATES PATENT OFFICE.

JOHN HENRY A. GARDINER, OF DOWNSERS GROVE, ILLINOIS.

INCANDESCENT-LAMP LOCK.

1,073,113. An improvement in the Specification of Letters Patent. Patented Sept. 16, 1913.

Application filed July 11, 1912. Serial No. 708,787.

To all whom it may concern:

Be it known that I, JOHN HENRY A. GARDINER, citizen of the United States, residing at Downers Grove, in the county of DuPage and State of Illinois, have invented certain new and useful Improvements in Incandescent-Lamp Locks, and I do hereby declare the following to be a full, clear, and exact description of the invention, such as will enable others skilled in the art to which it appertains to make and use the same.

This invention has for its object to provide a simple and efficient device for preventing incandescent electric lamps from being easily removed or becoming accidentally disengaged from their sockets and which, furthermore, may be employed to support a lamp shade holder and shade if desired, and consists in the features of construction and combinations of parts hereinafter fully described and particularly claimed.

In the accompanying drawings illustrating the invention, Figure 1 is a view in side elevation partly in section of an incandescent lamp lock and shade supporting fixture embodying my invention. Fig. 2 is a similar view of a modified form of construction of the same. Fig. 3 is a view in side elevation partly in section of a lamp lock embodying my invention showing it in the form in which it is applicable to existing styles of lamp sockets and devoid of lamp shade supporting means. Fig. 4 is a view in end elevation of the lamp lock shown in Fig. 3.

Incandescent lamps are apt to be accidentally disengaged from their sockets particularly in places where they are subjected to constant vibration, as on board cars of all kinds. Many lamps are also stolen in isolated places and the object of my invention is to provide a device whereby manual removal of the lamps from their sockets is rendered difficult and whereby accidental disengagement of the lamps from the sockets is entirely prevented.

A further object of my invention is to provide a locking device for incandescent lamps in which a non-conductive substance is employed for engaging the lamp with the exterior of the socket thus preventing possible short circuiting, as will be hereinafter more particularly explained.

My said device comprises a split ring 1 having projections 2 and 3 at its ends through which the screws 4 are passed by

means of which said ring may be contracted in a well-known manner. The said ring is provided with annular inwardly extending edge flanges 5 and 6 respectively, the said flange 5 being adapted to be drawn into contact with the outer face of the lamp socket rearwardly of the bead 7 usually provided therein and serving to prevent withdrawal of the ring from said socket by means of a relative telescopic movement of said parts. Said ring is further provided in its circumferential face at intervals with concavo-convex depressions 8 providing inwardly extending projections disposed parallel with and contiguous to the edge flange 6 thereof and between which and said edge flange 6 a split ring 9 of a non-conducting material, such as fiber, asbestos, or a similar substance, is engaged. Said ring 9 is of greater width than the depth of said flange 6 so that its inner circumferential face is disposed inwardly of the inner edge of said flange 6.

In use the ring 1 is primarily expanded to receive the lamp socket 10 and after the flange 5 has passed beyond said bead 7 of said socket the same is contracted to a degree sufficient to prevent it from becoming disengaged from said socket. The ring 9 being split is elastic so that the lamp plug 85 may readily pass through the same in being rotated as it is inserted into said socket 10 and, after the lamp 11 has been firmly secured within said socket 10, the said ring 1 is further contracted so as to compress said ring 9 around the lamp 11 at the juncture of the globe with the plug and to firmly engage the flange 5 of said ring with the lamp socket. When thus engaged the ring 9 exerts a more or less yielding pressure on 95 the bulb which, however, is sufficient to prevent the disengagement of the lamp therefrom. The said ring 9 being of a non-conducting material also prevents the possibility of a short circuit being established 100 between the shell of the socket 10 and the interior portion thereof, as will be apparent. The pressure of the ring 9 upon the bulb of the lamp is also distributed over so large an area as to prevent fracture of the same. 105 The said ring 1 may be equipped, as shown in Fig. 1, with a lamp shade supporting device 12 comprising the ring equipped with projections 13 in which the set screws 14 for engaging the shade 15 are 110 provided, the said ring being further provided with a plurality of projections 16

secured by rivets 17 or other means to said ring 1.

Instead of employing a ring 1 my invention may be embodied in the outer shell 18 of a lamp socket, as shown in Fig. —2—. The said shell 18 is adapted to pass over the lamp socket base consisting of porcelain or other material in the usual manner and may be provided with the usual means for engaging the same with said base, such means being omitted from illustration. In its outer end said shell 18 is provided with a longitudinal recess 19 extending inwardly from the outer end thereof and which is bordered by the flanges 20 through which the screws 21 pass by means of which the outer or mouth portion of said shell 18 may be annularly contracted. The split ring 22 of fiber or the like, is engaged in the annular recess 23 in the outer end portion of said shell 18 and is adapted to project over the threaded sleeve 24 carried by the porcelain base of the lamp socket and which is adapted to receive the lamp plug, so that, after the lamp has been mounted in said socket, the said shell 18 may be contracted at its mouth portion to throw said ring 22 into engagement with the lamp bulb contiguous to its junction with the plug and accidental removal of said lamp thus prevented. The said shell 18 may be equipped with the shade supporting device 12 of any suitable construction, the same being, in the instance

illustrated, identical with that shown in Fig. —1—.

I claim as my invention:

The combination with an incandescent electric lamp and its socket, of means engaged with both said parts for preventing separation thereof, said means comprising an annular flexible member circumferentially expansile, projections at the meeting ends of said member, set-screws engaged therewith for circumferentially contracting the said member, a split ring of a non-conducting material circumferentially expansile and contractile independently of said flexible member, and means engaging the latter with said flexible member for preventing relative movement of said parts in the direction of the axis of said flexible member, but permitting relative circumferential expansion and contraction of said split ring adapted to permit the lamp base or socket to be passed therethrough and to be contracted by contraction of said split member to engage said lamp base and its bulb around the juncture of said parts.

In testimony whereof I have signed my name in presence of two subscribing witnesses.

JOHN HENRY A. GARDINER.
